Herman Wilker, South Norwalk, Conn.

Application October 31, 1940, Serial No. 363,762

2 Claims. (Cl. 2—227)

This invention relates to apparel and more particularly to bifurcated garments such as pajamas, shorts, underwear, and similar garments worn by men, women, and children.

At the present time such garments are made with seams through the crotch and at the back and front to meeting edges of the garment sections together. This has been found expensive when manufacturing the garments and also uncomfortable when the garment is worn and in addition the crotch seam has a tendency to tear when subjected to strains.

Therefore, one object of the invention is to provide a garment wherein the crotch and the center portion of the seat are formed by portions of a section extending from the front of the garment through the crotch and upwardly at the back, thus eliminating a crotch seam and in addition providing a rear insert which permits added fullness to be provided at the back of the garment.

Another object of the invention is to provide a garment wherein the seat insert and the crotch portion are formed integral with the front section by a tongue or strip extending between the leg portions of the front section when the pattern for the front section is cut, the rear portion of the garment consisting of two sections sewed along their edges to side edges of the front section and the upturned middle strip of the front section. It will thus be seen that the number of seams necessary will be reduced to a minimum and that these seams will be so located that they may be easily made with a sewing machine.

Another object of the invention is to provide a garment so formed that an appreciable saving of material will be effected as well as a saving of time and labor when making the garment, the garment being also very strong and comfortable to wear.

With these and numerous other objects in view, our invention consists in the novel features of construction, combination and arrangement of parts as will be hereinafter referred to and more particularly pointed out in the specification and claims.

The invention is illustrated in the accompanying drawing wherein:

Fig. 1 is a front view of the garment.

Fig. 2 is a view looking at one side of the garment.

Fig. 3 is a rear view of the garment.

Fig. 4 is a fragmentary sectional view taken along the line 4—4 of Figure 3.

Fig. 5 is a view of the blank or pattern from

which the front section of the garment is made.

Fig. 6 is a view of the blanks or patterns for the back sections.

Fig. 7 is a perspective view of a person wearing a garment of the improved construction.

The improved garment has been illustrated as pajamas trousers but it is to be understood that the invention may be incorporated in underwear, shorts, and other bifurcated garments.

The garment has a body 1 formed with leg extensions 2 and consists of a front section 3 and rear sections 4 cut in accordance with the patterns or blanks shown in Figures 5 and 6. The front section 3 is of substantially oblong outline and midway the width of its upper end is formed with a fly 5 of conventional formation. The blank or pattern for the front section is also cut midway the width of its lower end to provide a tongue or strip 6 which extends longitudinally of the blank between leg forming portions 7 thereof, and attention is called to the fact that the blank is so cut that the strip is tapered or gradually reduced in width toward its upper end and the inner side edges 8 of the leg extensions or leg forming portions 7 converge upwardly along opposite side edges of the tapered tongue. The front section is of such width that when the front and rear sections are sewed to each other side portions of the front section extend rearwardly beyond opposite sides thereof an appreciable extent as clearly shown in Figures 2 and 3.

The two rear sections 4 correspond in length to the length of the front section 3 and while their outer side edges 9 are straight cut and extend at right angles to their upper and lower edges, their inner side edges have upper and lower portions 10 and 11, which are cut diagonally. Referring to Figure 6, it will be seen that the upper and lower portions 10 and 11 of each rear section converge toward their inner ends in a direction to gradually increase the width of the section and intersect midway the length of the section and it will also be noted that the lower portions 11 of these inner side edges conform to the angle of the inner side edges 8 of the leg extension 7 of the front section, and are also of the same length. By so cutting the edges 8 and 11, the side edges of the front and rear sections may be sewed together to form seams 12 along inner sides of the leg extensions 2 of the garment and the leg extensions will be completed when the outer side edges 9 of the rear section sections are sewed to side edges of the front section and form seams 13 which extend from the waistband to the lower ends of the legs. The

seams 12 terminate at opposite sides of the upper end of the tongue or strip 6 and it will be readily seen that when sewing the front and rear sections together, this is done by straight seams which can be easily and quickly sewed with a sewing machine. After the side edges of the sections have been sewed together, the tongue or strip 6 is passed rearwardly between upper ends of the leg extension and upwardly at the back of the garment with its side edge portions sewed to the upper portion 10 of the inner side edges of the rear section to form seams 14 and firmly unite the tongue or strip with upper portions of the rear section. The strip or tongue then constitutes a rear insert for the body of the garment and in addition forms a crotch strip. It will thus be seen that the usual rear seam extending at the center of the back of the garment will be eliminated and there will be no seam through the center of the crotch.

The fact that the tongue or strip 6 is tapered, as shown in Figure 5, causes it to gradually increase in width toward its upper end when sewed to the upper portions 10 of the side edges of the rear section. Therefore, a rear insert will be formed which adds to the comfortable fit of the garment, as well as permitting a person wearing the garment to lean over or stoop without likelihood of ripping the garment at the back. I have, therefore, provided a garment of the bifurcated type which may be very easily and cheaply manufactured due to the fact that the sections forming the same all have their adjoining side edges sewed together by straight seams. It will also be seen that a garment so formed will have added fullness at the rear and will be free from a center seam at the back and through the crotch.

From the foregoing description, the construction of our improved garment will be readily understood. It is understood that while we have particularly described the preferred construction best adapted to accomplish the functions set forth, it is obvious that various changes in form, proportion and in the minor details of construction may be resorted to, without departing from the spirit or sacrificing any of the principles of the invention.

Having thus described the invention, what is claimed is:

1. A bifurcated garment comprising a body having leg extensions, the said body and its leg extensions consisting of a front section and rear sections, the front section having body and leg forming portions and a tongue between the leg forming portions integrally united at its upper 50 end to the body-forming portion between upper

ends of the leg-forming portions, the rear sections being seamed along their outer side edges to the side edges of the front section, the inner side edges of the rear sections each having diagonally extending upper and lower portions converging toward their inner ends in a direction to gradually increase the width of the section and intersecting at the crotch level of the garment, the lower portions of the inner edges of the rear sections being seamed to inner side edges of the leg extensions of the front section and upper portions of the inner side edges of the rear sections diverging upwardly at the back of the garment, and said tongue being passed rearwardly between upper ends of the leg extensions and upwardly and seamed along its side edges to the diagonally extending upper portions of the inner edges of the rear sections to form a crotch portion integral with the front section and a seat portion at the back of the garment.

2. A bifurcated garment comprising a body having leg extensions and consisting of a front section and rear sections, the front section having an upper body-forming portion and being cut longitudinally from its lower end to provide leg-forming portions extending downwardly from its body-forming portion and a tongue between the leg-forming portions, the said cuts converging upwardly to provide downwardly tapered leg forming portions and an upwardly tapered tongue having its upper end integrally united to the body-forming portion at the crotch level of the garment, said rear sections being seamed along their outer side edges to side edges of the front section, the inner side edges of the rear sections each having diagonally extending upper and lower portions converging toward their inner ends in a direction to gradually increase the width of the section and intersecting at the crotch of the garment, the lower portions of the inner side edges of the rear sections being seamed to inner side edges of the leg-forming portions of the front section and form inner side seams for the leg extensions, the upper portions of the inner side edges of the rear sections diverging upwardly, and said tongue being carried rearwardly between upper ends of the leg extensions and upwardly at the back of the garment and being seamed along its side edges to the diverging upper portions of the inner side edges of the rear sections to form a seat-forming insert and a crotch portion integral with the said insert and the portion of the front section under the fly.
